UNITED STATES PATENT OFFICE.

WALTER REGINALD HUME, OF ADELAIDE, SOUTH AUSTRALIA, AUSTRALIA.

MACHINE FOR MAKING PIPES AND CONDUITS.

1,232,316.

Specification of Letters Patent.

Patented July 3, 1917.

Application filed January 13, 1914. Serial No. 811,870.

To all whom it may concern:

Be it known that I, WALTER REGINALD HUME, a subject of the King of Great Britain, residing at Flinders street, Adelaide, in the State of South Australia, Commonwealth of Australia, have invented certain new and useful Improvements in Machines for Making Pipes and Conduits, of which the following is a specification.

10 My invention relates to machines for making pipes and conduits, and has for its primary object to provide an improved construction, combination, and arrangement of parts in a machine of this character by 15 means of which a pipe or conduit may be provided with a cylindrical reinforcement constructed of wire and having sufficient rigidity to retain its cylindrical form so as not to collapse or sag under ordinary working conditions. One of the objects of the 20 present invention is to provide an improved machine which can be simply and durably constructed, which will be efficient in operation, and the product of which will be 25 inexpensive and serviceable. Another object is to provide a machine of improved construction whereby a cylindrical reinforcement of this character can be constructed of various strands of wire superimposed upon each other without interlacing. 30 Other and further objects will appear in the specification and be pointed out in the appended claims, reference being had to the accompanying drawings which exemplify 35 my invention in a preferred embodiment, and in which,

Figure 1 is a side elevation of the machine;

Fig. 2, a plan view of the same;

40 Fig. 3, an end elevation of the winding drum end of machine;

Fig. 4, an end elevation of the gear wheel end of machine;

45 Fig. 5, a sectional view of a portion of the small drum for winding reinforcement for small pipes;

Fig. 6, a spring pin device for the drum; and

50 Fig. 7, a diagram indicating the general arrangement of layers of reinforcing wires.

In each of the views similar marks of reference are used to denote similar or corresponding parts wherever they occur.

55 In Fig. 1 of the drawings and in the subsequent figures, 1 is a foundation frame

preferably made of strong rolled iron joists and suitably bedded. Upon this foundation frame two fixed gear standards 2 and 3 are securely bolted.

These gear standards support the main 60 driving shaft 4, the end of which projects beyond the standard 2 to form the drum spindle 5.

Upon the main driving shaft the main 65 gear wheel 6 is securely keyed or otherwise fastened, and at the outer end of the shaft the interchangeable speed wheels 7, 8 and 9, 10 are arranged, the last-named wheels being mounted on an auxiliary shaft 11 placed immediately below and in alinement with 70 the main driving shaft upon which said auxiliary shaft a chain wheel 12 is mounted.

The two bottom wheels 9 and 10 and the 75 chain wheel 12 rotate in unison, but the wheels 7 and 8 on the main shaft depend upon a sliding key 13 for their rotation, the key being embedded in the main shaft and being capable of engagement with either of the wheels 7 or 8 by the operation of the hinged lever 14 which is fitted with a controlling handle 15.

Belt wheels are shown at 16 and are secured to the belt shaft 17, in connection with which a clutch gear 18 is arranged, the sliding portion of the clutch having a 80 feather placed at 19 and a clutch handle or starting lever 20 connected therewith. The belt shaft is mounted upon frame brackets 21 which are cast upon the gear standards 2 and 3.

Upon the inner end of the drum spindle 5 a fixed cone 22 is fastened, and adjacent to the opposite end of the spindle the sliding cone 23 is arranged, the free end of the spindle being supported upon the hinged standard 24, which said standard is forcibly held in position by the toggle lever 25. The hinged standard is pivoted to the main 95 frame at 26.

The cylindrical winding drum is shown at 27, but is not a complete cylinder, inasmuch as its edges do not entirely meet. This will be understood more particularly on reference to 28 in Fig. 3 of the drawings wherein an open space is shown between the adjacent free edges, and is also illustrated in Fig. 1.

The drum, which is of sheet metal, is mounted upon spring rings 29 which are provided at each end, the tendency of the springs being to collapse inward; but to 110

these springs the arm brackets 30 are fastened and take an adjustable bearing upon the cones previously referred to, and by which means the springs may be extended 5 to suit the desired diameter of the drum according to the pressure exerted by the cones, as will be well understood.

A series of holes are circumferentially drilled through the ends of the drum, and 10 through these holes the small pins 31 project. These pins are mounted upon the ends of short springs 32, and can easily be depressed below the surface of the drum, as indicated in Fig. 6 of the drawings.

15 Referring now to the operative mechanism of the machine, it will be seen that an endless chain 37 passes over the previously mentioned chain wheel 12, and bearing upon the intermediate guide wheels 38 also passes 20 around the tension wheel 39. The slack of the chain may be adjusted by any simple form of tension gear, such as a screw and nut 40 or other convenient device.

Upon the frame of the machine I mount 25 a traveling carriage 41 which is guided by the horizontal wheels 42 which are grooved to engage the upper flange of the foundation frame joists. This frame is fitted with two chain wheels 43, and with a controlling 30 lever 44 which operates any simple form of clutch such as a double wedge-shaped bar placed above the endless chain in such a position as to render it capable of engaging either run of the chain which travels above 35 the wheels 43 in the opposite directions indicated by the adjacent arrows, (and capable also of disengaging with both) so as to traverse the carriage either backward or forward in accordance with the relative 40 movements of the chain, or to allow it to remain stationary when disengaged, as will be well understood.

Upon the carriage I mount a grooved 45 wheel 45 which serves as a guide for the wire reinforcement which is to be wound around the drum.

The wire reinforcement is illustrated in Fig. 7, the sequence of winding being as follows:—

50 A strand of wire from any suitable feed supply is passed under the guide wheel 45, and is fastened to one of the pins 31 upon the drum, the guide wheel having been placed opposite to one end of the drum.

55 By operating the starting lever 20 the machine is put in motion so that the drum commences to rotate, and simultaneously by means of the controlling lever 44 the carriage 41 is caused to traverse along the foundation frame, being operated by the endless chain 37. By this means two windings of 60 the wire are effected, that is to say, a single winding is made equal to the length of the drum and then by means of the lever 44 65 the carriage is actuated from the chain run-

ning in the opposite direction, and a return is thereby obtained.

For pipes of from four to five inches and up to twelve inches in diameter a spiral winding of about six inches pitch is used, 70 as indicated at 46 in Fig. 7, the pitch increasing as the diameter increases. After this has been done longitudinal or brace loops, as indicated at 47, are carried under and over the previously mentioned winding. 75

The longitudinal brace loops, of which there may be four in number, can best be applied by hand, and for this purpose a length of wire is taken and looped over one of the pins at the center of the wire; the 80 two ends are then bent under the drum, crossed at the middle, and from thence brought upward and on to the corresponding pin at the opposite end of the drum. After this operation I lay longitudinal 85 straight wires from end to end of the reinforcement. These wires are indicated at 48 in Fig. 7 and are applied by attaching the end of a piece of wire to one of the pins, then bringing it horizontally to and around 90 the corresponding pin on the opposite end of the drum, and returning it in the reverse direction after having coiled it at right angles one-eighth of a circle, that is to say, 95 around the next pin on the same end. This backward and forward setting of the wire is continued until the whole circumferential of the drum has been covered by a length of wire longitudinally placed from pin to pin.

For pipes which require to be specially 100 constructed for strength, I provide a supplemental series of wires as shown at 49. In spacing these supplemental wires a length of wire is attached to an end pin, and is stretched above the previously placed wires 105 not quite in a horizontal line but slightly at an angle so as to pass around the next opposite pin in succession at the opposite end of the drum, and then back to the starting end, but missing the next pin in succession as illustrated.

The final winding is achieved by means of the machine, and is either a single or return winding of close pitch as indicated 115 at 50, and by substantially the same operation of the machine as is described with regard to the first winding. These coils are preferably of about one inch pitch.

The variation in the winding pitch of the wires 46 and 50 is obtained by a variation 120 of the speed traverse of the traveling carriage 41, which can be easily effected by moving the sliding key 13 by aid of the hinged lever 14 and the controlling handle 15 so as to make the toothed wheel 7 a 125 driver while the wheel 8 becomes an idler, or alternatively to cause the wheel 8 to become a driver while the wheel 7 runs free as an idler, thereby decreasing or increasing the speed of the wheels 9 and 10 as may 130

be requisite to afford decreased or increased motion to the chain wheel 12 from which the endless chain 37 derives its motion.

While the machine is running the endless chain is continuously in motion, and is therefore always accessible for operating the traveling carriage 41 either backward or forward according to the position of the controlling lever 44, which when placed in middle position does not engage the chain, and therefore leaves the traveling carriage free.

It is to be understood that if the intermediate wires 47, 48 and 49 are placed in position by hand, the first winding of the wire 46 and the final winding 50 may be regarded as a continuous or unbroken process, and as the first and last windings embrace the intermediate wires between the internal and external coils there is no necessity for the separate interlacing of the wires, which are contained between the first and last windings. This forms an important feature of the reinforcement.

All free ends of the intermediate wires are clipped off or turned inward so as not to protrude, and the end of the final winding is secured by any convenient method, and is then clipped off. After this has been done the toggle lever is made to release the standard 24. The sliding cone 23 is withdrawn, and the drum is released.

The removal of the pressure of the cones against the arm brackets 30 enables the spring wheels 29 to slightly collapse the drum, thereby relieving the pressure of the coils of the reinforcement. When this has been done the pin springs 32 are depressed so as to carry the small projecting pin below the surface of the drum, thereby releasing the various wires connected therewith and allowing them and the whole of the reinforcement to be removed from the winding drum without hindrance or obstruction.

The constructional detail shown in Fig. 5 is for drums of small diameter, in which case the pins are made to operate as bent springs through holes or openings in the cones, the spring pins being fastened to a sliding collar 34 which is operated by the sliding push rod 35, whereby the pins are depressed to the position indicated by the dotted line.

What I claim is—

1. In a machine for manufacturing pipes and conduits, a main driving shaft, an auxiliary driving shaft driven thereby, means for varying the relative speeds of said shafts, a carriage movable along said machine, a flexible member operated by said auxiliary driving shaft and movable lengthwise along said machine, and means for successively connecting said carriage to said member and disconnecting it therefrom.

2. In a machine for manufacturing pipes and conduits, a driving shaft, an endless chain or belt connected with said driving shaft and comprising oppositely moving runs, a carriage reciprocable on said machine, and means for separately connecting said carriage to said runs of the endless chain or belt. 70

3. In a machine for manufacturing pipes and conduits, a winding drum consisting of a continuous plate of sheet metal having a narrow space between its abutting edges, a spring ring for supporting the drum, fixed and sliding cones arranged upon a rotatably mounted shaft, and means interposed between said cones and the drum for slightly expanding or increasing the diameter of said drum. 75

4. In a machine for manufacturing pipes and conduits, an expandible drum for winding reinforcement, a hinged standard for supporting the free end of the drum spindle, and a hinged or toggle lever for forcing and supporting such standard in a vertical position and for operating against a sliding cone, 80 substantially as described and as illustrated. 85

5. In a machine for manufacturing pipes and conduits, the combination with a rotary drum, of a series of radially projecting pins yieldably mounted to normally protrude beyond the peripheral surface of the drum for the attachment of reinforcing wires, and a wire directing carriage reciprocable longitudinally of said drum. 95

6. In a machine for manufacturing pipes and conduits, a rotary drum, a cone or casting arranged at the end of said drum, a series of diagonally projecting pins arranged to operate within inclined openings in said cone or casting, and means for reciprocating 100 said pins to extend and retract them with respect to the peripheral surface of said drum. 105

7. In a machine for manufacturing pipes and conduits, a drum, driving mechanism 110 for imparting motion to the drum, said mechanism comprising a main driving shaft having interchangeable speed wheels mounted thereon, an auxiliary shaft in parallel alignment therewith having interchangeable speed wheels thereon, a belt shaft geared to the main shaft, and a clutch gear for starting and stopping the machine. 115

8. In a machine for manufacturing pipes and conduits, a main driving shaft, an auxiliary driving shaft geared thereto, means for varying the relative speeds of said shafts, a chain wheel mounted upon the auxiliary shaft, a chain passing about said chain wheel and having oppositely moving runs, 120 a carriage adapted to be operated by said chain and means for successively connecting said carriage with the runs of said chain to reverse its direction of movement. 125

9. In a machine for manufacturing pipes 130

and conduits, the combination of a series of chain wheels and an endless chain operated from the main shaft by intermediate gearing, which said chain is arranged to traverse horizontally underneath the winding drum, and an ordinary adjustment nut and bolt for adjusting the tension of such chain.

10. In a machine for manufacturing pipes and conduits, a traveling chain, a traveling carriage having a wire guide thereon, a lever gear, and an engagement clutch whereby the

carriage is caused to engage said traveling chain for imparting backward or forward motion from the chain to the carriage, said clutch being releasable for enabling the carriage to remain stationary. 15

In testimony whereof I have affixed my signature in presence of two witnesses.
